(57) **CLAIM**

The ornamental design for a multimedia player, as shown and described.

DESCRIPTION

FIG. 1 is a perspective view of a multimedia player showing the claimed design;

FIG. 2 is another perspective view of multimedia player showing the claimed design;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is a partial enlarged view of an area labeled 9 in FIG. 1.

The dot-dash-dot broken lines in FIGS. 1 and 9 shown encircling the enlarged detail views are for annotative purposes only, while all other broken lines are included for the purpose of illustrating portions of the multimedia player; the broken lines form no part of the claimed design.
